P. PIRWITZ,
ATTACHMENT FOR CANTALIVER SPRINGS,
APPLICATION FILED APR. 19, 1921.

1,391,851.

Patented Sept. 27, 1921.

UNITED STATES PATENT OFFICE.

PAUL PIRWITZ, OF MARSHFIELD, WISCONSIN.

ATTACHMENT FOR CANTALIVER-SPRINGS.

1,391,851.

Specification of Letters Patent. Patented Sept. 27, 1921.

Application filed April 19, 1921. Serial No. 462,558.

To all whom it may concern:

Be it known that I, PAUL PIRWITZ, a citizen of the United States, residing at Marshfield, in the county of Wood and State of Wisconsin, have invented certain new and useful Improvements in Attachments for Cantaliver Springs, of which the following is a specification.

My invention relates to attachments for 10 cantaliver springs and more particularly to shock-absorbers for springs of this class used in connection with fast moving vehicles, such as automobiles and the like.

My object is to provide an attachment of 15 the character described, which will in reality from an auxiliary spring which can be conveniently attached to any ordinary cantaliver spring.

Another object in view is to provide a device of this character which, while assisting the cantaliver spring to take up vertical shocks, is specially adapted to absorb end shocks, as for instance, when both front 25 wheels of a fast moving car simultaneously strike an obstruction.

Minor objects will appear in the subjoined description.

The invention consists in the novel construction and arrangement of the several 30 parts, as will be hereinafter described and claimed, reference being had to the accompanying drawings, in which:—

Figure 1 is a side elevation of a front spring provided with my attachment; and 35 Fig. 2 is a similar view of a rear spring, the parts constituting the invention being indicated in both figures by shading.

Referring further to the drawings, the 40 numeral 1 indicates the frame of the vehicle, and 2, a cantaliver spring of any ordinary or preferred construction operatively mounted thereon. My attachment consists of a lower auxiliary spring 3, composed preferably of a fewer number of leaves than the cantaliver spring 2, and rigidly mounted on the axle 4 of the vehicle by means of a bolt 5 and a clip 6. Another clip 7, located between the clip 6 and the inner end of the auxiliary spring, serves to further hold the 45 leaves in engagement with each other, while the upper leaf of the auxiliary spring at its inner end is pivotally connected to a bracket 8, which is rigidly secured to the inner end of the cantaliver spring 2 by one of the bolts 50 55 9 which secures said spring to the vehicle frame 1.

The outer or heavy end of the auxiliary spring 3 extends outwardly beyond the axle 4, and is adapted at its outer end to pivotally engage the upper end of a shackle 10. 60

The upper portion of my attachment consists of a single leaf 11 rigidly secured to the under side of the cantaliver spring 2. It projects outwardly over the outer end of the auxiliary spring 3 and curves downwardly 65 and inwardly and is pivotally connected at its lower end to the lower end of the shackle 10 below the outer end of the auxiliary spring 3, whereby the upper and lower yielding portions of my device are adapted for limited 70 longitudinal movement relatively to each other, which proves to be of great advantage in absorbing end shocks, as will be pointed out more fully farther on.

It will also be observed that with my present arrangement, the outer springy end of the upper leaf 11 is connected with the heavy outer end of the lower auxiliary spring 3, while the inner springy end of the auxiliary spring 3 is connected by means of 80 the bracket 8 with the heavy inner end of the cantaliver spring 2.

The upper leaf 11 is rigidly held against longitudinal movement on the cantaliver spring 2 by means of a bolt 12 at the outer 85 end of said spring. The clips 13 further assist in holding the upper leaf 11 in firm engagement with the under side of the cantaliver spring, while at the same time permitting the separate leaves which form said 90 spring to glide upon each other as the spring moves up and down.

While the attachments for the front and rear springs are alike in mechanical principle and construction, yet in the front spring, 95 the heavy end of the auxiliary spring 3 is the forward end, whereas the reverse is true of the rear spring.

In the operation of my device it will be seen that having the upper leaf 11 project as 100 it does over the outer end of the lower auxiliary spring 3, enables said upper leaf to be made longer, and consequently more springy than would otherwise be possible; and the fact that the leaf 11 engages the 105 lower end of the shackle 10, permits the employment of a greater curve at the outer end of said upper leaf. It is also pointed out that the shackle 10 may be made of different lengths, and when desired, longer than is 110 shown in the drawings, so that without changing the lower auxiliary spring 3, an

upper leaf 11 of different lengths, and consequently of different degrees of resiliency may be employed with the same vehicle.

It is apparent that a cantaliver spring provided with my attachment will have a greater vertical travel, but particular attention is called to the special adaptability of the device to absorb end shocks, as for instance, when the front wheels of a rapidly moving vehicle simultaneously strike an obstruction or depression in the roadway. Since the axle is fastened to the lower auxiliary springs 3, the major part of the endwise shock as just described, will be imposed upon said auxiliary spring, and as the heavy end of the front auxiliary spring is the forward end thereof, the strain imposed upon the spring will be in the direction of its greatest resiliency—a concave strain, so to speak, instead of a convex. The outer curved end of the upper leaf 11 cooperates sufficiently with the auxiliary spring 3 to instantly recover the front wheels to their original position after an initial endwise shock, and thereby also precludes the possibility of breaking the inner leaf of the auxiliary spring 3.

The fact that the lower auxiliary spring 3 projects outwardly a material distance beyond the axle to which it is secured, serves to permit the upper leaf 11 to be made longer and consequently more springy.

The great practical value of the above arrangement becomes apparent, when it is considered that end shocks in rapidly moving vehicles are very sudden but not very great, whereas the vertical strain is often comparatively great. In the construction shown, the auxiliary spring 3 yields to end shock on the front wheels in the direction of its least strength and greatest resiliency, but resists vertical shock in the direction of its greatest strength and power of resistance.

45 The curvature of the inner end of the auxiliary spring 3 may be made greater or less according to the peculiar requirements of each case or the preferences of the individual user, and hence in the drawings I have shown one of these auxiliary springs provided at its inner end with a very considerable curve, and the other with a much less curve.

Having now described my invention, what 55 I claim as new and desire to secure by Letters Patent is:—

1. A device of the character described, comprising an upper section adapted to be secured to the under side of a cantaliver spring; a lower auxiliary spring section adapted to be secured, at a point spaced inwardly from the outer end thereof, to the axle of the vehicle; a shackle pivotally connecting the outer end of the upper section 60 with the projecting outer end of the lower

section; and means for pivotally connecting the inner end of the lower section to the inner end of the cantaliver spring with which the device is to be used.

2. A device of the character described, 70 comprising an upper section adapted to be secured to the under side of a cantaliver spring; a lower auxiliary spring section adapted to be secured, at a point spaced inwardly from the outer end thereof, to the 75 axle of the vehicle; a downwardly extending shackle pivotally connected at its upper end to the projecting outer end of the lower section, with the outer end of the upper section projecting outwardly over said shackle 80 and curving downwardly and inwardly and pivotally connected at its lower end with the lower end of the shackle; and means at the inner end of the lower section for pivotally connecting the same to a fixed bearing. 85

3. A device of the character described, comprising an upper section adapted to be secured to the under side of a cantaliver spring; a lower auxiliary spring section composed of a plurality of leaves, with its 90 heavy end outward, and adapted to be secured, at a point spaced inwardly from said outer end, to the axle of the vehicle; a downwardly extending shackle pivotally connected at its upper end to the projecting outer 95 end of the lower section, with the outer end of the upper section projecting outwardly over said shackle and curving downwardly and inwardly and pivotally connected at its lower end with the lower end of the shackle; and means at the inner end of the lower section for pivotally connecting the same to a fixed bearing. 100

4. A device of the character described, comprising an upper section formed of a 105 single leaf adapted to be secured to the under side of a cantaliver spring in flat engagement therewith; a lower auxiliary spring section, composed of a plurality of leaves, with its heavy end outward, and 110 adapted to be secured at a point spaced inwardly from said outer end to the axle of the vehicle; a downwardly extending shackle pivotally connected at its upper end to the projecting outer end of the lower section 115 with the outer end of the upper leaf section projecting outwardly over the shackle on the outer projecting end of the lower section and curved downwardly and inwardly and pivotally connected at its lower end with the 120 lower end of the shackle; and means at the inner end of the lower section for pivotally connecting the upper leaf thereof to a fixed bearing.

5. In a device of the character described 125 for the front wheel of a vehicle, an upper section adapted to be secured to the under side of a cantaliver spring; a lower auxiliary spring section resilient and springy at its inner end and comparatively rigid at 130

its outer forward end and adapted to be secured, at a point spaced inwardly from said forward end, to the axle of the vehicle; a downwardly extending shackle pivotally connected at its upper end to the forwardly projecting end of said lower section, with the outer end of the upper section projecting outwardly over said shackle and curved downwardly and inwardly and pivotally connected at its lower end with the lower end of the shackle, the inner end of said

lower section to which the axle is attached being curved inwardly and upwardly; and means at said inner end for pivotally connecting the same to a fixed bearing; whereby lateral rearward strain imparted to the axle of the vehicle will press said lower spring section in the line of its least resistance. 15

In testimony whereof I affix my signature. 20

PAUL PIRWITZ.
